UNITED STATES PATENT OFFICE

93,258

DESIGN FOR A COMBINED VENDING MA- CHINE AND LAMP OR ARTICLE OF SIM- ILAR NATURE

Ralph A. Vogel, Columbus, Ohio, assignor to The Columbus Vending Company, Columbus, Ohio,
a corporation of Ohio

Application May 31, 1934, Serial No. 51,970

Term of patent 14 years

To all whom it may concern:

Be it known that I, RALPH A. VOGEL, a citizen of the United States of America, residing at Columbus, in the county of Franklin and State of Ohio, have invented a new, original, and ornamental Design for a Combined Vending Machine and Lamp or Article of Similar Nature, of which the following is the specification, reference being had to the accompanying drawing, forming a part hereof.

Figure 1 is a perspective view of a combined
vending machine and lamp, showing my new design.

Figure 2 is a perspective view of my vending
machine, with the lamp thereof omitted.

I claim:

The ornamental design for a combined vending machine and lamp or article of similar nature, as shown.

RALPH A. VOGEL.
